AUTOMATIC ADJUSTMENT OF CIRCUIT
BREAKERS

Montford Morrison, Montclair, N. J., assignor to
Westinghouse X-Ray Company, Inc., a Corpora-
tion of Delaware

Application December 31, 1930. Serial No. 505,789

4 Claims. (Cl. 250—34)

My invention relates to X-ray apparatus and has particular relation to an X-ray circuit in which the X-ray tube is protected by a circuit breaker interposed in the supply circuit.

5 More particularly stated my invention has reference to a method of regulating the circuit breaker in accordance with the current supplied to an X-ray tube, in such a manner that the greater the amount of current flowing through 10 the tube, the greater the rapidity with which the circuit breaker will open the circuit, when some abnormal condition takes place in the circuit.

In X-ray circuits some type of safety device is usually employed to protect the X-ray tube 15 against damage but these devices have heretofore been responsive to a fixed amount of current which when exceeded opens the circuit. Other types of safety devices, such as circuit breakers, although adjustable are responsive to the particular setting to which the device is adjusted and it occasionally happens that great damage is done to the X-ray tube and apparatus before the circuit is opened under abnormal conditions.

It is accordingly an object of my invention to 25 provide in an X-ray circuit a circuit breaker which is automatically adjusted.

Another object of my invention is the provision 30 of a device associated with a circuit breaker which automatically adjusts the breaker in accordance with the current flowing in an X-ray tube circuit.

A further object of my invention is the provision 35 of a device associated with a circuit breaker interposed in an X-ray system which increases the rapidity of operation of the circuit breaker in response to the occurrence of abnormal conditions, in the system, and simultaneously increases the current in the system.

Still further objects of my invention will be 40 become apparent to those skilled in the art by reference to the accompanying drawings wherein:

Figure 1 is a diagrammatical view of an X-ray circuit in which one form of my invention is utilized; and

45 Figure 2 is a diagrammatical view of an X-ray circuit showing the utilization of a modification of my invention.

Referring now to the drawings in detail I have shown in Fig. 1 an auto-transformer 2 arranged 50 to be energized from a suitable source of commercial potential, such as an alternating current generator 3, through suitable conductors L1 and L2. A suitable switch 4 is provided in the conductor L2 for the purpose of opening and closing the supply circuit to the auto-transformer 2. A conductor 5 extends from one end of the wind-

ing of the auto-transformer to one end of a primary winding 6 of a high-tension transformer 7, while another conductor 8 extends from an adjustable arm of the auto-transformer through a coil 9, of a circuit breaker 10, to a contact terminal 12. A conductor 13 extends from another contact terminal 14 to the other end of the primary winding 6 and the circuit breaker 10 is provided with a contact member 15, which when the breaker is operated to the closed position, 60 completes the circuit to the primary winding 6. 65

A low tension transformer 16 is arranged to have its primary winding 17 receive energization from a suitable source such as the generator 3. A supply conductor L3 extends from the generator 70 to one end of the primary winding 17 while a conductor L4 extends from the generator, through a suitable switch 18, to a movable contact arm 19 of a rheostat 20. A conductor 21 then extends from the windings of the rheostat 20 to the other 75 end of the primary winding 17 for completing the circuit. The movable contact arm 19 of the rheostat 20 is associated with the circuit breaker 10 so as to adjust the breaker in accordance with movements of the rheostat when the latter is operated to vary the current supplied to the primary winding 17, as more fully hereinafter explained. 80

The secondary winding 22 of the low tension transformer 16 is connected by means of conductors 23 and 24 to the filament of an X-ray tube 25. The secondary winding 26 of the high tension transformer 7 is connected at one end by means of a conductor 27 to the anode of the X-ray tube 25 and the other end of this winding is connected, by means of a conductor 28 to the conductor 23. It thus becomes readily apparent that when the primary windings 6 and 17 are energized the filament of the X-ray tube 25 is heated by means of the secondary winding 22 and that energy will flow between the electrodes of the tube from the secondary winding 26 of the high tension transformer 7. 85 90 95

Referring now to the adjustment of the circuit breaker in accordance with the current flowing in the X-ray tube I have shown in this modification a base 32 which is provided with a pair of bearing brackets 33 in which a shaft 34 is journaled.

The contact arm 19 of the rheostat 20 is secured 100 to one end of this shaft 34 and a control knob 35 is secured to the other end of this shaft for operating the contact arm 19. A cam surfaced roller 36, having a notched portion 37, is rigidly secured to this shaft 34 with its periphery in 105 110

contact with a plunger 38 which passes through the coil 9 of the circuit breaker 10.

Rotation of the control knob 35 moves the contact arm 19 to vary the current supplied to the transformer 16 and also rotates the cam surfaced roller 36. Rotation of this latter roller raises or lowers the plunger 38 depending upon the direction of rotation of the knob 35. The raising or lowering of this plunger 38 thus changes the length of travel of the plunger necessary to open the circuit breaker 10 in response to abnormal conditions which would cause excessive current to flow through the coil 9.

The operation of this embodiment of my invention is as follows: the switch 18 is first closed to energize the transformer 16 for heating the filament of the X-ray tube. The control knob is then rotated in a counter-clockwise direction, as viewed from Fig. 1, and moves the contact arm 19 over the windings of the rheostat 20 to increase the current to the desired amount. The switch 4 is then closed to energize the auto-transformer 2 and the circuit breaker 10 is closed to thus energize the high tension transformer 7 and the X-ray tube 25.

The rotation of the control knob 35 in a counter-clockwise direction also rotates the cam surfaced roller 36, which due to its configuration, limits the downward movement of the plunger 38.

As the circuit breaker 10 is opened by an upward movement of the plunger 38, in response to excessive currents flowing through the winding of the coil 9, the limiting of the downward movement or the raising of the plunger 38 by further rotation of the knob 35 and the cam roller 36, lessens the length of upward travel of the plunger necessary to trip the breaker 10.

In this manner the greater the amount of current flowing through the tube 25, the shorter the length of travel of the plunger 38 necessary to open the breaker upon any abnormal conditions occurring in the circuit. It consequently follows that the greater the amount of current flowing in the circuit the greater will be the rapidity with which the breaker will trip under all abnormal conditions.

Rotation of the knob 35 and arm 19 in a clockwise direction reduces the amount of current flowing in the circuit by excluding the windings of the rheostat 20 from the circuit and at the same time rotates the cam roller 36 to allow further downward movement of the plunger 38. When the windings of the rheostat 20 are entirely excluded from the circuit, or in other words when the arm 19 is moved in a clockwise direction to its limit of travel, the cam roller 36 is rotated until the plunger 38 no longer contacts the roller 36 but drops into the notched portion 37. In this position the plunger is in its extreme downward position which requires the greatest length of travel before tripping the breaker 10 and opening the circuit.

It is to be noted, however, that with the plunger in this latter position and even though the minimum amount of current is flowing through the X-ray tube 25, the breaker is sufficiently calibrated to allow opening of the circuit upon occurrence of all abnormal conditions without damage resulting to the circuit or to the X-ray tube.

Referring now to the modification shown in Fig. 2 I have shown in addition to the circuit breaker 10, another circuit breaker 42 interposed in the conductor 5, and provided with a coil 43 in series with the primary winding 6 and

the auto-transformer 2, in the same manner as the coil 9 of the circuit breaker 10. The conductor L3 connecting the source of energy 3 with the primary winding 17 of the heating transformer 16 is herein provided with the switch 18 and the rheostat 20 although the conductor L4 might just as readily be provided with these latter members as in the modification previously described.

The conductor L4 connecting the other side of the source 3 with the primary winding 17 has a coil 44 surrounding a magnetic core 45 and connected in series with this latter coil 44 is another coil 46 which surrounds the elongated core 38 of the circuit breaker 10. The core 45 is pivotally secured to a double faced rotatable cam 47 each face of which is provided with a lateral projection 48 and 49 respectively. An adjustable coil spring 50 is secured to one of these projections 49 and to a fixed point of the apparatus for tensioning the cam 47.

The other extension 48 of the cam 47 contacts a core or plunger 52 of the circuit breaker 42 which is surrounded by the winding 43. The purpose of the adjustable spring 50 is to adjust the circuit breakers 10 and 42 in order to preset these breakers for opening when current flowing through the system exceeds a predetermined amount.

The windings 44 and 46 are oppositely poled so that the current flowing through the coil 44 draws the core 45 downwardly while the current flowing through the coil 46 moves the core 38 upwardly. As the current flowing from the source 3 to the primary winding 17 is increased by the rheostat 20 it naturally follows that the current flowing in the coils 44 and 46 is likewise increased thus moving the respective cores 45 and 38 still further in the directions just mentioned. The upward movement of the core 38, being in the direction necessary to open the breaker 10, renders the remaining distance of travel to trip the breaker considerably less which allows a rapid opening of the breaker by excessive currents due to abnormal condition flowing through the coils 9 or 46.

The downward movement of the core 45 rotates the cam 47 which due to the contact of the lateral projections 48 with the core 52 raises this latter core in the same manner as the core 38. By increasing the tension of the coil spring 50 the current flowing through the coil 44 is thus limited by the choking effect of this coil and the current flowing through the coil 46 is likewise limited due to the series connection of these two coils 44 and 46. In consequence of this limiting of the current in the coils 44 and 46, the cores 38, 45 and 52 are also limited in their movement in response to the current flowing in the circuit, as the current is varied by the regulation of the rheostat 20.

It is obvious from the foregoing that the operation of this modification of my invention is identical to the operation of the embodiment previously described differing only in the mechanical structure in the one instance associated with the rheostat and the circuit breaker, and in the latter modification the association of the plurality of circuit breakers with the circuit and responsive to the current flowing therethrough, as regulated by the rheostat, is entirely electrical.

It can, therefore, be readily seen that I have provided a circuit breaker that may be employed in an X-ray tube circuit, which is automatically adjusted in accordance with the current flowing

in the circuit and in which the rapidity of operation increases with an increase of current in the circuit.

Although I have shown and described several embodiments of my invention I do not desire to be limited thereto as various other modifications of the same may be made without departing from the spirit and scope of the appended claims.

What is claimed is:

- 10 1. In an X-ray system, an X-ray tube, a high tension transformer for energizing said X-ray tube, a source of energy for said high-tension transformer, a circuit breaker interposed between said source and said high tension transformer responsive to the occurrence of abnormal conditions in said system for disconnecting said high tension transformer from said source, a low tension transformer for supplying heating currents to said X-ray tube, a rheostat connected to said low tension transformer for varying the current supplied to said X-ray tube, and electrical means associated with said circuit breaker and in series with said rheostat for adjusting said circuit breaker in response to operation of said rheostat.
  - 20 2. In an X-ray system, an X-ray tube, a high tension transformer for energizing said X-ray tube, a source of energy for said high tension transformer, a circuit breaker interposed between said source and said high tension transformer responsive to the occurrence of abnormal conditions in said system for disconnecting said high tension transformer from said source, a low tension transformer for supplying heating currents to said X-ray tube, a rheostat connected to said low tension transformer for varying the current supplied to said X-ray tube, and electrical means associated with said transformer and in series with said rheostat for adjusting said circuit breaker and altering the rapidity of operation of the same in response to the occurrence of abnormal conditions in said system.
  - 25 3. In an X-ray system, an X-ray tube, a high
- tension transformer for energizing said X-ray tube, a source of energy for said high tension transformer, a circuit breaker interposed between said source and said high tension transformer responsive to the occurrence of abnormal conditions in said system for disconnecting said high tension transformer from said source, a low tension transformer for supplying heating currents to said X-ray tube, a rheostat connected to said low tension transformer for varying the current supplied to said X-ray tube and means electrically responsive to the variations of current supplied to said X-ray tube by operation of said rheostat and associated with said circuit breaker for changing the rapidity of operation of said circuit breaker in response to the occurrence of abnormal conditions in said system simultaneously with the operation of said rheostat.
- 80
4. In an X-ray system, an X-ray tube, a high tension transformer for energizing said tube, a source of energy for said high tension transformer, a circuit breaker interposed between said source and said high tension transformer responsive to the occurrence of abnormal conditions in said system for disconnecting said high tension transformer from said source, a low tension transformer for supplying heating currents to said X-ray tube, said circuit breaker provided with a plurality of windings, one of said windings being connected in series with said source and 105 said high tension transformer, and the other of said windings being connected in series with said source and said low tension transformer and a rheostat connected in series with said last mentioned winding and transformer for varying the 110 current supplied to said X-ray tube whereby an increase of current supplied to said X-ray tube by operation of said rheostat simultaneously increases the rapidity of operation of said circuit breaker in response to the occurrence of ab- 115 normal conditions in said system.
